UNITED STATES PATENT OFFICE.

JOHN GEORGE BODENSTEIN, OF STAATSBURG, NEW YORK.

ICE-HOOK.

SPECIFICATION forming part of Letters Patent No. 311,639, dated February 3, 1885.

Application filed October 13, 1884. (No model.)

To all whom it may concern:

Be it known that I, JOHN GEORGE BODENSTEIN, of Staatsburg, in the county of Dutchess and State of New York, have invented a new and Improved Ice-Hook, of which the following is a full, clear, and exact description.

This invention relates to certain new and useful improvements in ice-hooks used for shifting blocks and cakes of ice.

10 The object of my invention is to simplify the construction of the same by making the pushing and pulling points of a single piece, all as hereinafter fully described, and pointed out in the claims.

15 Reference is to be had to the accompanying drawings, forming a part of this specification, in which similar letters of reference indicate corresponding parts in all the figures.

Figure 1 is an enlarged side view of my improved ice-hook. Fig. 2 is an edge view of the same. Fig. 3 is a cross sectional view of the same on the line $\alpha\alpha$, Fig. 1. Fig. 4 is a side view of the hook and handle.

On one end of a strong pole, A, an eyebolt, 20 B, is held by bolts and a collar, F, or otherwise, the eye C projecting beyond the end of the pole and being triangular in shape. A bar, D, having a triangular cross-section, is pointed at each end, the bar being twisted at 25 or near the middle, so that the ridges will be

at opposite sides, the bar D being bent at the twisted parts, so that when the bar D is held in the eye of the eyebolt the two ends will be at different inclinations to the pole. The end a is used as a pusher and the end b is used as 35 a puller. The bar D is held in place on the eye C by a wedge, E. The pushing and pulling points are held by a single eyebolt, and to remove both points neither the eyebolt nor the collar need be removed. The cost of the 40 ice-pick is thus reduced and the construction simplified.

Having thus described my invention, I claim as new and desire to secure by Letters Patent—

1. An ice-hook formed from a bar, D, having a triangular cross-section and pointed at its ends, the bar being twisted at the middle of its length and bent at the twisted part, substantially as herein shown and described. 45

2. In an ice-hook, the combination, with 50 the triangular eyebolt B C, secured to a handle, of the triangular pointed bar D, twisted and bent, as described, and the wedge E, for locking the bar in the eye, substantially as herein shown and described.

J. GEORGE BODENSTEIN.
